LIQUID DISTRIBUTING DEVICE

Wallace A. Beardsell, East Natick, and Warren H. Hay, Beverly, Mass., assignors to Monsanto Chemical Company, St. Louis, Mo., a corporation of Delaware

Application May 23, 1949, Serial No. 94,802

4 Claims. (Cl. 137—166)

1

The present invention relates to an improved liquid distributing device.

It is often necessary both in laboratory and mill scale operations to supply a plurality of machines, devices or other apparatus which are performing identical operations with uniform streams of liquid in which the stream supplied to each machine is equal in amount and rate of flow to the stream which is being supplied to each of the other machines, devices, etc. For example, in textile mills it is often necessary to apply a tint, oil or the like to a plurality of cotton rovings and to apply equal amounts and rates of such tint etc. to each roving. In chemical plants and laboratories it is often necessary to supply a number of similar reactors in which a chemical reaction is being carried out with equal amounts and rates of a liquid catalyst, chemical compound or chemical composition. In accomplishing these objects it has usually been the practice to provide separate metering devices so that the same quantity and rate of liquid constituent could be supplied to each of such machines, devices, reactors, etc. This practice is not economical, however, both from the standpoint of first cost and of maintenance.

It is one object of this invention to provide a simple device for dividing and distributing a single metered stream of liquid into a plurality of equally metered streams of liquid.

A further object of this invention is to provide an improved liquid distributing device which is adapted for use under widely varying conditions and which is adapted to supply uniform amounts of liquid and rates of flow to a large or small number of operating machines, devices or reactors without stopping the operation of the device to meet changing demands and conditions.

Still further objects and advantages of this invention will be apparent from the following description when taken together with the accompanying drawing and the appended claims.

The liquid distributing device of the present invention includes a cylindrical trough or pan having a slightly conical-shaped bottom which is provided with a central aperture and with an annular raised portion or ridge which is spaced from the center of the pan. The pan bottom consists of concentric annular portions which slope slightly downward toward the center of the pan, the outer periphery of the inner annulus being slightly raised above the inner periphery of the outer annulus, thereby forming an annular ridge spaced from the center and from the side wall of the pan. The lower por-

2

tion of the pan is divided into pockets or compartments by radially extending partitions which extend an equal distance up the side wall of the pan and an equal distance along the bottom toward the center of the pan. Each of the pockets or compartments thus formed is open at the top and toward the center of the pan, and has a discharge opening in the bottom of the pan positioned adjacent to and radially outward from the annular ridge. The device also includes rotating means for discharging a metered stream of liquid against the outer or side wall of the pan above the compartments therein at a constant angular velocity.

15 A preferred embodiment of the liquid distributing device of this invention is illustrated in the drawings, in which

Fig. 1 is a plan view of the liquid distributing device, and

20 Figure 2 is a vertical sectional view taken along line 2—2 of Figure 1.

In the drawings, in which like numerals refer to like parts, 10 refers to a cylindrical trough or pan which comprises a base plate 11, outer wall 12 and a reinforcing bottom portion 13 all of which are cemented together to form a liquid-tight, unitary structure. The pan 10 is mounted on a suitable support (not shown). The base plate 11 has inwardly sloping upper surfaces providing an annular raised portion or ridge 14 approximately midway between its outer edge and center. The pan 10 is divided into pockets or compartments 15 of equal volume by means of radially positioned L-shaped partitions 16 which fit snugly against the plate 11 and outer wall 12 and are cemented thereto. The top edges of partitions 16 are beveled. The inner edges of partitions 16 are spaced concentrically from the center of plate 11 and terminate between the center of plate 11 and the annular ridge 14.

30 The compartments 15 each have discharge openings 17 in plate 11 which are spaced concentrically from the center of plate 11 and immediately adjacent to and radially outward of the annular ridge 14. The diameter of each discharge opening 17 is the same and is substantially equal to the distance between the partitions 16. Each discharge opening is internally threaded to receive a standard pipe fitting 18 which is equipped with a shut-off valve 19. Although only one pipe fitting and valve is illustrated it is to be understood that each discharge opening 17 is provided with a pipe fitting and valve if it is desired to employ each discharge opening for liquid distributing purposes. An overflow opening 20 is

40 provided in the center of plate 11. This opening 50

is also internally threaded for receiving a suitable pipe fitting.

Liquid is distributed to pan 10 by means of a curved or bent tube 21, the vertical axis of which coincides with the vertical center axis of plate 11. The tube 21 is provided with an integral gear wheel 22 and is supported in ball bearings 23 and 24 which are fastened to a suitable support. Tube 21 is also provided with a horizontal portion having a nozzle 25 at the discharge end, which rotates in a plane immediately above the partitions 16, and a funnel opening 26. The gear 22 is driven by a worm gear 27 which is in turn driven by means of an electric motor 28. The motor is fastened to a suitable support. Since gear 22 and tube 21 are integral, the tube 21 is caused to rotate about its vertical axis when gear 22 is rotated.

The pan 10 and partitions 16 may be constructed out of any rigid material which does not distort or change dimensions on aging. As examples of materials which are suitable for use may be mentioned non-corrosive metals or alloys such as aluminum, copper, brass, stainless steel, etc. and plastic materials such as styrene, polyacrylates, polymethacrylates and the like. The pan 10 and partitions 16 can be cast integrally from thermosetting resins such as phenol-formaldehyde resins, melamine-aldehyde resins and the like or thermoplastic resins of the type described above.

The operation of the device is as follows:

A metered stream of liquid, having a substantially constant volume of flow per unit of time, is continuously supplied (from a conventional metering device and supply tube not shown) to the funnel opening 26 of tube 21 which is being driven at constant angular velocity through gears 22 and 27 by electric motor 28. The liquid is continuously discharged through nozzle opening 25 against the outer wall 12 of pan 10 above the L-shaped partitions 16. The liquid then flows down the inner surface of outer wall 12 in the form of a film and thence into the compartments 15. The upper beveled edges of partitions 16 serve the purpose of dividing the film of liquid flowing down the wall 12 so that each compartment receives an equivalent amount of liquid. The liquid film after reaching the bottom of the pan 10 flows downwardly toward the discharge openings 17 and then out through the pipe fitting 18. It is thus possible by using the device illustrated in Figures 1 and 2 to obtain, continuously, 24 separate and uniform streams of liquid from the single metered stream supplied to tube 21.

This device can be operated efficiently and with extreme flexibility. For purposes of illustration, it is assumed that a mill, plant, or laboratory has 24 devices, machines or reactors (not shown) that each require a stream of liquid which is equal in volume and rate of flow to each stream of liquid being supplied to each of the other devices, etc. Each of these devices is connected to a discharge opening 17 in pan 10 by means of pipe fitting 18, equipped with a valve 19, and suitable piping (not shown). By operating the liquid distributing device continuously it is possible to supply each device, etc. with a uniform stream of liquid. By increasing or decreasing the rate of flow and quantity of liquid supplied to tube 21 it is possible to increase or decrease the volume and rate of flow of each stream of liquid discharged from the liquid distributing device, proportionately.

If one or more of the devices, etc. to which the stream of liquid is being supplied is shut down for any reason or is not placed in operation, the

discharge line to that particular device is cut off by closing valve 19. The liquid in this particular compartment then accumulates or collects until it rises above that segment of the annular ridge 5 or annular raised portion 14 which lies between the partitions of the particular compartment and flows downwardly toward the overflow opening 20, out through this opening and into a storage tank or reservoir (not shown) from whence it is pumped back as a metered stream of liquid, to tube 21. This does not in any way affect the streams of liquid being discharged from the other compartments, but merely enables the operator to cut out any number of devices, etc. which no longer require a supply of liquid without affecting other devices, etc. which are still in operation. By using proper piping arrangements it is also possible to divert a stream of liquid from the discharge opening in any particular compartment to auxiliary machines, devices, etc. which are being held in stand by position or to devices, etc. which are being placed in operation.

The uniformity of flow of the liquid stream discharged from the discharge opening in each compartment depends primarily on the nature of the metered liquid, the speed of rotation of tube 21, the distance that the liquid travels from the point where it strikes the wall to the discharge opening and the slope of the bottom of pan 10, the most important factor being the speed of rotation of tube 21. Each compartment obtains only an increment of the total quantity of liquid discharged through tube 21 on each revolution of the tube. Therefore, it is necessary in order to obtain uniform streams of liquid to make the time interval between each increment as small as possible. In other words, it is necessary to have the tube 21 rotate rapidly so that the increments supplied to each compartment or chamber follow in rapid order. Due to the fact that the liquid flows down the wall and bottom of the pan in the form of a film the pulsating effect of each increment is evened out and by the time the film reaches the discharge opening 17 the rate of flow is uniform. The practical limitations on the maximum speed of rotation of tube 21 are those imposed because of undue splashing due to centrifugal force and uneven distribution from tube 21 due to wind effects, that is, a non-uniform stream of metered liquid resulting from eddy currents of air created by the rotation of tube 21.

The liquid distributing device of this invention is useful for handling a large variety of liquids which have the property of wetting a surface and have sufficient viscosity to form and maintain a film. Thus, liquids such as water, water solutions of metallic salts, water emulsions, silica aquasols and other colloidal solutions, oils, oil emulsions and the like can be successfully divided and distributed as uniform streams of liquid by the use of the device described herein. In some instances the wettability of liquids and the uniformity of division and distribution can be improved by adding a small amount of wetting agent to the liquid before it is supplied to tube 21. This also tends to reduce splashing of the liquid when it strikes the outer wall of the pan since the liquid tends to spread out along the wall in the form of a film instead of rebounding in the form of droplets.

With the foregoing considerations in view, it is evident that many changes may be made in the size of the device, the number of compartments, the shape and size of the partitions, the

location of annular ridge 14 and other factors, as will be apparent to those skilled in the art, without departing from the spirit of the present invention. Thus the size of the device may be varied considerably depending on the quantity and rate of flow of liquid which it is desired to supply to each device, reactor etc. If the amounts to be supplied are large, than larger devices are preferably employed. On the other hand, if the amounts to be supplied are small, a much smaller device can be used successfully.

The number of compartments 15 in the device may be varied considerably depending upon the number of devices, reactors, etc. to which it is desired to supply streams of liquid. Since the advantages of this device over single metering devices from an economic view point increases as the number of machines, reactors, etc. which require the supply of uniform streams of liquids are increased, it is, of course, desirable to employ a distributing device which is divided into a large number of compartments or chambers 15.

The size and shape of the partitions 16 may also be varied considerably as is evident when it is considered that the primary function of the partitions is to confine the film of liquid deposited on the outer wall to a fixed wall area and to a fixed area on the bottom surface of the pan 10 before discharge through discharge opening 17, which areas are equal in each of the compartments 15. Thus the thickness, height, configuration and to some extent the distance of the inner edge of the partitions from the center of the pan 10 are immaterial to the proper functioning of the device as long as the compartments have equal outer wall and bottom surface areas as described above. Of course, the partitions 16 should extend radially inward at least as far as the annular ridge 14 in order to insure the flow of the liquid into the proper discharge opening or into the central overflow opening 20 without permitting spillage or flow into an adjacent compartment.

The annular ridge portion 14 may be spaced farther from or closer to the center of pan 10 than is illustrated in Figures 1 and 2. It is preferred, however, to locate the annular ridge portion 14 not more than midway between the outer edge and the center of the pan 10 and as close to the center of the pan 10 as possible and still leave a circular area surrounding the discharge opening 20 to provide for the overflow of liquid from each compartment. Under these conditions the increment of liquid film deposited on the outer wall 12 by the rotating tube 21 travels a sufficient distance before reaching the discharge opening 17 so that the subsequent increments of liquid merge with the remainder thereof and thus provide a uniform instead of pulsating flow. The discharge openings 17 should always be sufficiently large to discharge the liquid as it reaches the opening otherwise the liquid tends to build up in the compartment and the rate of discharge through the opening will increase or decrease with increasing or decreasing head. Moreover, the discharge openings 17 should be located immediately adjacent to the annular ridge portion 14 or at the base thereof, to prevent the accumulation of liquid between the opening and the annular ridge portion. An accumulation of liquid at this point is undesirable especially if the liquid is apt to gel or become highly viscous since it necessitates frequent cleanings and

also because the flow of the liquid from the opening is apt to be non-uniform.

What is claimed is:

1. A liquid distributing device comprising a stationary cylindrical pan having a bottom portion and a vertically extending side wall, said bottom portion being provided with a central opening and an upstanding annular wall spaced from the center of said pan, the bottom portion of said pan including a conical portion which slopes downwardly from said side wall to said annular wall and another conical portion which slopes downwardly from the top of said annular wall to said central opening, said pan being divided into a plurality of compartments each of which has a single discharge opening in the bottom thereof positioned immediately adjacent to and outwardly from said annular wall, said compartments being defined by said side wall, annular wall and first mentioned conical portion and by partitions which extend radially inward from said side wall, the area of the outer wall of said compartments being equal and the areas of the bottom portions of said compartments being equal, said partitions extending vertically upward above said annular wall whereby excess liquid in said compartments may flow over said annular wall and thence into said central opening without running into other compartments, and rotating means for directing a metered stream of liquid against the inner surface of the side wall of said pan at constant angular velocity.
2. A liquid distributing device comprising a stationary cylindrical pan having a bottom portion and a vertically extending side wall, said bottom portion being provided with a central opening and an upstanding annular wall spaced outwardly not more than midway from the center toward the outer edge of said pan, the bottom portion of the pan including a conical portion which slopes downwardly from said side wall to said annular wall and another conical portion which slopes downwardly from the top of said annular wall to said central opening, said pan being divided into a plurality of compartments each of which has a single discharge opening in the bottom thereof spaced concentrically from the center of said pan and positioned immediately adjacent to and outwardly from said annular wall, said compartments being defined by said side wall, annular wall and first mentioned conical portion and by partitions which extend radially inward from said side wall to some point between the central opening and said annular wall, the area of the outer wall of said compartments being equal and the area of the bottom portions of said compartments being equal, said partitions extending vertically above said annular wall whereby excess liquid in said compartments may flow over said annular wall and thence into said central opening without running into other compartments, and rotating means for directing a metered stream of liquid against the inner surface of the side wall of the pan at constant angular velocity.
3. A liquid distributing device comprising a stationary cylindrical pan having a bottom portion and a vertically extending side wall, said bottom portion being provided with a central opening and an upstanding annular wall spaced outwardly not more than midway from the center toward the outer edge of the pan, the bottom portion of the pan including a conical portion which slopes downwardly from said side wall to said annular wall and another conical

portion which slopes downwardly from the top of said annular wall to said central opening, said pan being divided into a plurality of compartments each of which has a single discharge opening in the bottom thereof spaced concentrically from the center of said pan and positioned immediately adjacent to and outwardly from said annular wall, said compartments being defined by said side wall, annular wall and first mentioned conical portion and by partitions which extend radially inward from said side wall and terminate at concentrically spaced points located inwardly of said annular wall, the area of the outer wall of said compartments being equal and the area of the bottom portions of said compartments being equal, said partitions extending vertically above said annular wall whereby excess liquid in said compartments may flow over said annular wall and thence into said central opening without running into other compartments; a curved tube extending both vertically and horizontally, the vertical axis of which is coincident with a vertical center line through the bottom of said pan and the horizontal portion of which terminates in a nozzle adjacent to the outer wall of said pan and positioned above said partitions, means for supporting and rotating said tube at constant angular velocity and means for supplying said tube with a metered stream of liquid.

4. A liquid distributing device comprising a stationary cylindrical pan consisting of a bottom portion and a vertically extending side wall, said bottom portion being provided with a central opening and an annular ridge which is spaced from the center of said pan, said bottom portion having a conical portion which slopes

downwardly from said side wall to said annular ridge and another conical portion which slopes downwardly from the top of said annular ridge to said central opening, said pan being divided into compartments by equally spaced radially extending partitions, each of which extends an equal distance from the side wall toward the center of said pan, said partitions extending from the side wall to at least the top of said annular ridge, said partitions extending vertically above the top of said annular ridge whereby excess liquid in said compartments may flow over said ridge and thence into said central opening without running into other compartments, 15 each of said compartments having a discharge opening in the bottom thereof positioned immediately adjacent to and outwardly from said annular ridge, said discharge openings being of equal diameter and substantially as wide as the distance between the partitions, rotating means 20 for directing a metered stream of liquid against the inner surface of said side wall at constant angular velocity, and means for supplying said rotating means with a metered stream of liquid.
